UNITED STATES PATENT OFFICE.

JACOB H. SCHEUER, OF NEW YORK, N. Y.

DESIGN FOR A MILITARY HAIR-BRUSH.

42,954.

Specification for Design.

Patented Aug. 27, 1912.

Application filed April 22, 1912. Serial No. 692,501. Term of patent 7 years.

To all whom it may concern:

Be it known that I, JACOB H. SCHEUER, a citizen of the United States, residing in the city, county, and State of New York, have invented a new, original, and ornamental Design for Military Hair-Brushes, of which the following is a specification, reference being had to the accompanying drawing, forming part hereof.

In the drawing the figure represents a perspective view of a military hair brush showing my new design.

I claim—

The ornamental design for a military hair brush as shown.

JACOB H. SCHEUER.

In presence of—

ANDREW BOLAND,
H. G. KIMBALL.
